CLAIM

The ornamental design for a laterally cushioned article holder, as shown.

DESCRIPTION

FIG. 1 is a perspective view of a laterally cushioned article holder in accordance with the present invention;

FIG. 2 is a front view thereof;

FIG. 3 is a rear view thereof;

FIG. 4 is a side view thereof;

FIG. 5 is an opposing side view thereof;

FIG. 6 is a top view thereof; and,

FIG. 7 is a bottom view thereof.
